PUMP PLUNGER VALVE AND STEM

Filed May 24, 1927

INVENTOR
HUGH S. BERKEY

Hugh S. Berkey
ATTORNEY

UNITED STATES PATENT OFFICE

HUGH S. BERKEY, OF HUNTINGTON BEACH, CALIFORNIA

PUMP PLUNGER VALVE AND STEM

Application filed May 24, 1927. Serial No. 193,761.

My present invention relates to improvements in deep well pumps; and more particularly to deep well pumps in which provision is made for the positive opening and closing of a working valve incidentally to the reciprocation of a plunger.

As is well known, in the operation of reciprocating pumps by means of sucker rods whose sections are connected by means of threaded couplings, such sections are liable occasionally to separate; and efforts to establish connection therebetween have heretofore been complicated or defeated by a tendency of the lower or "fish" sections to rotate, instead of remaining stationary, during efforts to reunite said sections. It is accordingly an object of my invention to provide means for preventing relative rotation of a sucker rod section which extends into a reciprocable plunger.

Further objects of my invention, including the use of a novel valve which may be referred to as an inverted plumb-bob, positively held against a shoulder and seated reciprocably within an elongated cage, and optionally involving the use of a novel valve guard and/or a reversible valve seat which serves as a coupling, may be best appreciated from the following description of an illustrative embodiment of my invention, taken in connection with the appended claims and in the accompanying drawings, in which

Fig. 1 may be referred to as a substantially median section through a pump organization embodying my invention, parts being broken away.

Fig. 2 is an enlarged view, comparable with the upper portion of Fig. 1, but taken in a plane at right angles thereto,—substantially as indicated by the line 2—2 of Fig. 1.

Fig. 3 is a view, similarly enlarged, comparable with the lower portion of Fig. 1, but taken at right angles thereto,—substantially as indicated by the lines 3—3 of Fig. 1.

Fig. 4 is a horizontal sectional view taken substantially as indicated by the line 4—4 of Fig. 1.

Referring to the details of that specific embodiment of my invention chosen for purposes of illustration, 11 being a pump cylin-

der of any desired character and length, 12 is a plunger cylinder,—which may closely interfit, although adapted to reciprocate therein; and the upper end of said plunger is shown as provided with a head member 13, which is laterally cut away,—to provide parallel vertical faces 14, 14', through which may be cut fluid outlet apertures 15, 15', and/or other apertures as best shown in Figs. 2 and 4.

Instead of providing the mentioned plunger, or its equivalent, with an upwardly opening valve, or securing said plunger directly to a sucker rod comprising a lowermost section or coupling 16, I show the mentioned rod or coupling as directly connected only with a subsidiary or valve-operating rod 17,—this subsidiary rod being capable of a limited reciprocation relatively to said plunger, through a vertically-extending aperture 18 in the head 13, or its equivalent. The extent of this relative reciprocation may be limited by, for example, the adjustment of a lock nut 19, or its equivalent, shown on said subsidiary rod and as adapted to engage an oppositely disposed shoulder 20, on said head; but it should be understood that a primary purpose of the "lost motion" or relative movement here referred to its a suitable and positive manipulation of a downwardly-opening valve, of any preferred character, secured at or near the lower end of the subsidiary rod 17.

I show a double-ended valve seat element 21 as secured relatively to the cylindrical plunger body 12 by means of an intermediate or male-female coupling element 22, provided with a vertically-extending passage 23, of sufficient diameter to permit not only a free reciprocation of the subsidiary rod 17, or its equivalent, but also a free passage of pumped fluid therethrough; and, in case it is considered desirable to protect the mentioned parts, and/or a valve element 24, carried by the subsidiary rod 17, by means such as a guard element 25 (shown as resembling in

form an elongated cage, and optionally provided with a threaded opening 26, suitable for use in lifting a standing valve organization, not shown, at will) this protecting or guard element may advantageously be so employed as to serve as a lock nut, holding the seat

element 21, or its equivalent, securely in an adjusted position relatively to the plunger cylinder 12 or the intermediate member 22, or an equivalent part.

5 Although the valve element 24 may be of any preferred character, I show the same as frusto-conical in general form, as retained in engagement with a shoulder 27 at the upper end of a reduced portion 28 of the rod 17, 10 as rounded for a stream-line effect at its lower end 29, and as retained by means of a nut or nuts 30 upon a threaded extension of said reduced portion.

The subsidiary rod 17 being provided with 15 a hexagonal or other non-circular section 31, the apertured plunger head 13 is shown as so shaped, below the circular opening 20 through which the said rod extends, as to provide parallel, flat surfaces 32, 32', between 20 which a hexangular body 33 may be slidably interfitted. This slideable body is shown as provided with a non-circular opening, corresponding in shape to the outline of the non-circular section 31 of rod 17. The slideable 25 body 33 may be held in place by means such as a nut 34; and its length, position and relationship to the parallel surfaces 32, 32' may be such, with regard to the movement permitted between nut 19 and shoulder 20, that 30 it can never, during pumping or other operations, escape from slideable retention between said parallel surfaces,—this construction providing a preferred means to prevent relative rotation between the subsidiary rod 17 and 35 the plunger comprising cylinder 12, or its equivalent.

The described "lost-motion" relationship between the subsidiary rod 17, carrying and operating the valve 24, is obviously such that, 40 during each descending stroke, the valve 24 is opened before the plunger descends; and said valve is afterwards closed before the plunger rises. The shape of the valve 24, as related to its seat, is favorable not only to 45 tight closure but to free flow. The fit of the pump plunger 12 within the outer cylinder 11 may be such as to permit, upon a suitable application of rotative power, a transmission of torque through all of the mentioned movable parts, in such manner that thread 26 may 50 engage (whenever the plunger is lowered for that purpose) any special upstanding member correspondingly threaded for use in "pulling" a standing valve organization (not 55 shown); but the fit of the plunger within its cylinder and its mass are nevertheless to be presumed such as ordinarily to prevent free relative rotation therebetween. Accordingly, 60 the subsidiary rod 17, with any number of sections of sucker rod attached thereto, is to be understood as sufficiently held, by means including the described interfitting non-circular member and surfaces 31, 32, 32' and 33, 65 to prevent any rotation thereof, during the

screwing or unscrewing of sections of pump rod, or during analogous operations.

Obviously any desired valves and/or auxiliary devices, not shown, may be placed above and/or below a plunger of the indicated character; said plunger may be of any preferred type, with or without special packing; and although, for convenience of description, I have used terms as "above" and "below", it will be appreciated that a plunger constructed and equipped in somewhat the indicated manner may be used in any position whatever and operated by any desired means.

70 Although I have herein described a single complete embodiment of my invention, it should be understood not only that various features thereof may be independently used but also that numerous modifications might be devised, by those skilled in the arts to which this case relates, without the slightest departure from the spirit and scope of this invention, as the same is indicated above and in the following claims.

75 I claim as my invention:

1. A pumping organization comprising: a 80 pump plunger reciprocable by a sucker rod; a valve-operating rod extending through said plunger; and means constantly preventing relative rotation between said plunger and said valve operating rod.

85 2. A pumping organization comprising: a pump plunger reciprocable by a sucker rod; a valve-operating rod extending through said plunger; and means constantly preventing relative rotation between said plunger and said valve operating rod,—said last mentioned means comprising a non-circular section on said valve-operating rod, an apertured member mounted in said plunger; and a non-circular member interposed therebetween.

90 3. A pumping organization comprising: a pump plunger reciprocable by a sucker rod; a valve-operating rod extending into said plunger; and means constantly preventing relative rotation between said plunger and said valve operating rod,—said last mentioned means comprising a non-circular section on said valve-operating rod, an apertured member mounted in said plunger; and a non-circular member interposed therebetween, said last mentioned member being secured by threaded means engaging said rod.

95 4. A pumping organization comprising: a pump plunger reciprocable by a sucker rod; a valve operating rod slidably movable through said plunger; a valve seat carried by said plunger; a frusto conical valve positively reciprocable by said valve operating rod relatively to said seat; and means for constantly preventing rotation between said plunger and said valve operating rod, said valve seat being a double ended seat which is engaged by a lock nut and an apertured 100 guard.

5. A pumping organization comprising: a pump plunger reciprocable by a sucker rod; a valve operating rod slidably movable through said plunger; a valve seat carried by said plunger; a frustro conical valve positively reciprocable by said valve operating rod relatively to said seat; and means for constantly preventing rotation between said plunger and said valve operating rod, said 10 valve seat being a double ended seat which is engaged by a member serving as a lock nut and as an apertured guard, said apertured guard being provided with a threaded vertically extending opening.
- 15 6. A pumping organization comprising: a pump plunger reciprocable by a sucker rod; a valve operating rod slidably movable through said plunger; a valve seat carried by said plunger; a frustro conical valve positively reciprocable by said valve operating rod relatively to said seat; and means for constantly preventing rotation between said plunger and said valve operating rod, said valve seat being a double ended seat which is 20 engaged by a lock nut and an apertured guard, said apertured guard being provided with a threaded vertically extending opening; said rotation preventing means comprising a non-circular section of said valve operating rod, an apertured member comprised in said plunger and a non-circular member interposed therebetween.
- 25 7. A pumping organization comprising: a pump plunger reciprocable by a sucker rod; a valve operating rod slidably movable through said plunger; a valve seat carried by said plunger; a frustro-conical valve positively reciprocable by said rod relatively to said seat; and means for constantly preventing rotation between said plunger and said 30 valve operating rod.

In testimony whereof, I have hereunto set my hand at Huntington Beach, California, this 18th day of May, 1927.

45 HUGH S. BERKEY.
